FLIER FOR SPINNING MACHINES

Henry C. Herr and Harvey E. Herr, Buffalo, N. Y.,
assignors to Herr Manufacturing Company,
Inc., Buffalo, N. Y., a corporation of New York

Application April 27, 1934, Serial No. 722,662

13 Claims. (Cl. 117—26.5)

This invention relates to improvements in the fliers employed in connection with spinning machines.

One of its objects is to provide a flier of this character which is so designed and constructed as to produce an even, constant and minimum thread tension during the spinning operation, all of which attributes are particularly essential to the spinning of synthetic threads and yarns.

10 Another object of the invention is the provision of a balanced flier having means for developing or creating, during the high speed motion of the flier, a force for counter-acting the centrifugal force developed by the flier wires.

15 A further object is the provision of a flier for spinning machines which is simple and inexpensive in construction, and which is efficient in operation and assures a minimum uniform tension on the threads at all times.

20 In the accompanying drawing:—

Figure 1 is a side elevation of a bobbin and spindle showing the improved flier operatively associated therewith. Figure 2 is an enlarged top plan view thereof. Figure 3 is a cross section taken in the plane of line 3—3, Figure 2. Figure 4 is a bottom plan view showing the invention in connection with an eccentric type of flier. Figure 5 is a cross section showing this type of flier in position on the bobbin.

25 Similar characters of reference indicate corresponding parts throughout the several views.

Referring to Figures 1—3 of the drawing, 10 indicates a spindle of the usual tapered form and 11 a bobbin mounted thereon. The flier-body, 35 which is detachably mounted on the bobbin-spindle, may be of any suitable construction, that shown in the drawing consisting of an anchoring sleeve or journal 12 for attachment to the tapered end of the spindle, a hub 13 rotatably mounted on the journal and flier wires 14 suitably carried thereby and projecting from one side thereof. By way of example, we have shown these wires connected to a member 15 projecting from one side of the hub and retained in 45 loops 16 formed therein, a clamping ring or segment 17 being employed for securely holding the wires against displacement relative to the retaining loops. In the drawing, two flier wires are depicted, one having a depending thread- 50 engaging eye at its outer end which during the rotation of the flier assumes the outwardly-deflected position seen by full lines in Figure 1.

55 Projecting from that side of the flier hub 13 diametrically opposite to that of the flier wire supporting member 15, is a member 18 which is

designed to provide a means for counter-balancing the weight of the flier wires and their attaching means when the flier is at rest, and which is further so designed as to develop or generate a force to counteract the centrifugal force developed by the flier wires when the flier is in motion. To this end, the member 18 is provided with a weight-forming element 19 which acts to counter-balance the wire-bearing side of the flier and which is so shaped as to provide an air 10 deflector which functions to produce an outwardly-acting force during the variable high speed operation of the flier to correspondingly compensate or counteract the centrifugal force developed by the flier wires. In its preferred 15 form, this element 19 is in the form of a flange projecting from the outer edge of the member 18 and is substantially V-shaped in plan, the apex thereof facing toward the hub-axis to thereby provide a convex inner surface against which 20 the air is impinged during the high speed operation of the flier and a concave outer surface where a vacuum is created to thereby exert a pulling force or effect on that side of the flier which counteracts the centrifugal force of the flier 25 wires with the result that the flier revolves evenly and uniformly about the spindle to maintain an even tension on the threads at variable speeds.

To prevent any tendency of the flier to tilt, as in response to a downward pull on the flier 30 when the thread is being taken off the bobbin, we preferably provide the flier-member 18 with air-impinging or deflecting surfaces or depressions 20 which are located in the top side of and adjacent the marginal side edges of said member 35 and against which the air is deflected to maintain the flier in a level position at all times, the air acting on these surfaces in a cushioning or shock-absorbing manner to resist tilting of the 40 flier.

In Figures 4 and 5, we have shown our invention in connection with an eccentric type of flier, 21 indicating the attaching sleeve thereof having a substantially cam-shaped flange 22 at its lower end which is adapted to be passed through the 45 opening 23 in the inverted cup member or ferrule 24 of the bobbin 25 during the application and removal of the sleeve to and from the spindle 26. The flange 22 is arranged to bear against the underside of the top wall of the cup member 50 in the manner shown in Figure 5. Mounted on the sleeve 21 is a wire-attaching member 27 and projecting from the diametrically opposite side thereof is a weight-balancing member 28, similar to that heretofore described, and functioning to 55

produce the same results of counter-balancing the weight and centrifugal force of the flier wires. The eccentric flange 22 is disposed in a direction crosswise relatively to the members 27, 28 so that its weight is evenly distributed in opposite sides of the flier-axis. As seen in Figure 4, the bottom or flanged end of the sleeve 21 is substantially elliptical in shape, one end of the ellipse forming the flange 22 to provide a bearing of maximum extent with the ferrule and still retaining the proper balance of the flier as well as permitting the ready application and removal of the flier to and from the bobbin.

We claim as our invention:—

1. A flier for spinning machines, comprising a hub, one or more flier wires projecting from one side of said hub, and a member projecting from the diametrically opposite side of said hub and having an air impact face extending generally in a circumferential direction for generating a force counter to that of the centrifugal force of the wires when the flier is in motion.

2. A flier for spinning machines, comprising a hub, one or more flier wires projecting from one side of said hub, and a member projecting from the diametrically opposite side of said hub for counter-balancing the weight of the wires when the flier is at rest, said member having a portion thereon shaped to compress the air at the inner side thereof to generate a force to counter-act that of the centrifugal force of the wires when the flier is in motion.

3. A flier for spinning machines, comprising a hub, a wire-supporting member projecting from one side of said hub, flier wires attached to said supporting member, a member projecting from the diametrically opposite side of said hub and having a circumferentially extending deflecting element shaped to create a vacuum outwardly thereof and to generate a force counter-acting the centrifugal force developed by the wires when the flier is in motion.

4. A flier for spinning machines, comprising a body having a flier wire projecting from one side thereof, and a member projecting from the diametrically opposite side of said body and including a part shaped to compress the air inwardly thereof and produce a vacuum outwardly thereof to develop a force to counter-act the centrifugal force of the wire when the flier is in motion.

5. A flier for spinning machines, comprising a hub, one or more flier wires projecting from one side of said hub, attaching means for the wires, and a member projecting from the diametrically opposite side of said hub and having an air deflector thereon converging inwardly toward said hub for creating an outward force to counter-act the centrifugal force of the wire when the flier is in motion.

6. A flier for spinning machines, comprising a hub, one or more flier wires projecting from one side of said hub, attaching means for the wires, and a member projecting from the diametrically opposite side of said hub and having a substantially V-shaped air deflector thereon with the apex thereof facing the hub-axis.

7. A flier for spinning machines, comprising a hub, one or more flier wires projecting from one side of said hub, attaching means for the wires, and a member projecting from the diametrically opposite side of said hub and having a transversely-extending flange thereon having a convex inner side and a concave outer side.

8. A flier for spinning machines, comprising a hub, a member projecting from one side thereof and having a flier-wire attached thereto, and a member projecting from the diametrically opposite side of said hub to balance the weight of said wire attaching member and wire and including an air-deflecting element for developing a force counter-acting the centrifugal force developed by the wire when the flier is in motion, said weight-balancing member also having air-impacting faces to prevent tipping of the flier in response to an external pull thereon.

9. A flier for spinning machines, comprising a sleeve adapted for attachment to a bobbin-spindle and terminating at its lower end in a substantially cam-shaped flange, means projecting from one side of said sleeve for supporting a flier wire, and means projecting from the opposite side of said sleeve for counter-balancing the weight of the flier wire and its supporting means, said sleeve-flange extending substantially in a direction at right angles to the flier wire and said first and second-named means with its weight evenly distributed on either side of the sleeve-axis.

10. A flier for spinning machines, comprising a sleeve adapted for attachment to a bobbin-spindle and terminating at its lower end in a substantially cam-shaped flange, means projecting from one side of said sleeve for supporting a flier wire, and means projecting from the opposite side of said sleeve for counter-balancing the weight of the flier wire and its supporting means and including an air deflecting element for generating a force to counter-act the centrifugal force developed by the flier wire when the flier is in motion, said sleeve-flange extending substantially in a direction at right angles to the flier wire and said first and second-named means with its weight evenly distributed on either side of the sleeve-axis.

11. A flier for spinning machines, comprising a hub, one or more flier wires projecting from one side of said hub, a member projecting from the diametrically opposite side of said hub for generating a force counter to that of the centrifugal force of the wires when the flier is in motion, and air-impinging surfaces formed on said member adjacent the side edges thereof for resisting tilting of the flier.

12. A flier, comprising a journal adapted for attachment to a bobbin-spindle, a hub mounted on said journal to revolve thereon and having a member projecting from one side thereof including means for detachably securing a flier wire thereto, and a member projecting from the opposite side of said hub for counter-balancing the weight of the flier wire and having an air impact face extending generally in a circumferential direction and shaped to generate a force counter to that of the centrifugal force of the flier wire when the flier is in motion.

13. A flier, comprising a body having a flier wire projecting from one side thereof, and means at the opposite side of said body for counter-balancing the weight of the wire when the flier is at rest and having an air impact face thereon extending generally in a circumferential direction and shaped to generate a force counter to that of the centrifugal force of the flier wire when the flier is in motion.
